CLAIM

I claim the ornamental design for a rolling bedside vanity table, as shown and described.

DESCRIPTION

FIG. 1 is a perspective view of a rolling bedside vanity table, showing my new design;

FIG. 2 is a front elevational view of FIG. 1;

FIG. 3 is a rear elevational view of FIG. 1;

FIG. 4 is a right elevational view of FIG. 1;

FIG. 5 is a left side elevational view of FIG. 1;

FIG. 6 is a top plan view of FIG. 1;

FIG. 7 is a bottom plan view of FIG. 1; and,

FIG. 8 is a rear perspective view of a rolling bedside vanity table shown in an environment of use.

The broken lines show environment that forms no part of the claimed design.

1 Claim, 5 Drawing Sheets
